ADAM WAECHTER, OF MAPLEWOOD, NEW JERSEY, ASSIGNOR TO GROOVE LOCK CO., INC.,
OF NEW YORK, N. Y., A CORPORATION OF NEW YORK

FASTENING DEVICE FOR BAG FRAMES

Application filed April 21, 1931. Serial No. 531,712.

My present invention relates to fastening devices for hand and other types of bag frames, and has for its object to provide an improved fastening device by means of which to secure such frames in closed relation and which is adapted to be released to permit the frames to be swung away from each other in the act of opening the bag.

One of the objects of the invention is to provide for securing the frames together and for releasing the same, a movable member movable longitudinally along the frames which is so mounted for movement upon one of the frames that when the frames are in closed relation the movable member will appear for the sake of compactness and as well for esthetic purposes to belong to each of the frames and to occupy, without being bulky or clumsy, a central superposed position along the frames.

An object of the invention is the provision of a fastening device of the above character which will possess points of convenience and efficiency, which will be economical to manufacture and at the same time be simple in construction and operation, while possessing the advantages of being sturdy and providing for compactness.

Another object of the invention is the provision of a construction in which, when the frames are closed, the movable member, besides serving as an ornamental topping extending centrally along the tops of the abutting frames, will function in the capacity of a sliding latch by means of which to secure and release the frames in abutting condition. There is a fixed catch lug to be interengaged and released by the latch member accordingly as the latter is moved to and from its latching position, and the latch member is itself provided with an opening to permit the catch lug to be received in a position in which it can be interengaged and released by the latch member.

With the above and other objects in view, the invention consists in the improved fastening device for bag frames and in the form, construction and relative arrangement of its several parts, as will be hereinafter more fully

described, illustrated in the accompanying drawing, and subsequently claimed.

In the drawing, wherein I have illustrated one simple and practical embodiment of the invention, as reduced to practice, and in which similar reference characters designate corresponding parts throughout the several views:—

Figure 1 represents a side view of a hand bag frame equipped with a fastening device made in accordance with the present invention, the fastening device being shown in released position and the frame members being shown in partially open relation;

Fig. 2 is a fragmentary elevation, showing the frame members in closed relation with the latch member moved into its latching position;

Fig. 3 is a longitudinal sectional view, taken on the line 3—3 of Fig. 1 and showing the guide strips for the latch member;

Fig. 4 is an enlarged cross sectional view taken on the line 4—4 of Fig. 2; and

Fig. 5 is a similar view taken on the line 5—5 of Fig. 2.

Referring with more particularity to the accompanying drawing, the numerals 10 and 11 designate cooperating frame members which carry the body (not shown) of the hand bag in any well-known or customary manner, and these frame members are united at their terminals by pivot means 12 so as to be swung towards and away from each other in the usual way in the act of closing and opening the bag.

To one of the frame members, herein shown to be the frame member 10, I secure the means for mounting the latching device by means of which the two bag frames may be secured in closed relation or released for opening movement in the act of opening the bag. The mounting means comprise two elongated guide strips 13 and 14 which are united by soldering, spot-welding, or other suitable means to the front wall part 15 of the frame member 10. In the present embodiment, the strips 13 and 14 are in the form of rods and they are secured in place in direct longitudinal alignment with each other and with a gap 16 intervening between

75

their respective inner ends 13' and 14'. According to an important feature of the arrangement, said rod-like guide strips 13 and 14 are secured to the front wall 15 in such manner that, when the two frame members 10 and 11 are in closed relation, said aligned guide strips will occupy a position centrally of the combined width dimensions of the two frame members. Mounted in this way, the two aligned guide strips extend part way over the frame member 10 and also part way over the frame member 11 when the latter is closed in contact against the frame member 10, as best illustrated in Figs. 4 and 5. The guide strip 13 at its outer terminal, is provided with a finger piece which may be made in the form of a knob 17, and this knob protrudes beyond the adjacent end of the frame member where it may be readily seized by the fingers. The other guide member 14 has a plain outer end, since, as will be presently observed, the latch slide itself carries the finger piece or knob at this end of the arrangement.

18 denotes a hollow latch slide which is sleeved upon the two guide strips 13 and 14 for longitudinal shifting movement thereon. In the present embodiment, this latch slide is of tubular form and is of a length substantially equal to the length of the frame members, so that when its plain end 18' abuts against the knob 17, the finger piece or knob 19 provided on its opposite end will be closely adjacent the frame member although protruding beyond the same for ready seizure by the fingers. At its bottom and for its full length, the tubular latch slide 18 has an opening or slot 20 between parallel longitudinal edges 21 and 22. This longitudinally extending slot provides the necessary space for the accommodation of the front wall 15 of the frame member 10, to which the two guide strips are secured, and as well for the free unobstructed movement of the back wall 23 of the frame member 11, it being observed from an inspection of Figs. 4 and 5 that when the frame members are in closed relation the back wall 23 comes in flatwise contact against the front wall 15 and closely under the two guide strips.

The latch slide 18, in the front thereof, and within the region of the gap 16, is provided with an opening 24 which is in communication with the bottom opening 20. The purpose of the opening 24 is to permit the passage of a catch lug 25, upstanding from the rear wall 23 of the frame member 11, into and out of the gap 16 within the latch slide 18. In said gap 16 and within the hollow interior of the latch slide, there is secured to the latch slide a stop 26, the location of which is such that it will engage the free end 14' of the guide strip 14 and thereby arrest or limit the outward movement of the latch slide at the precise position at which the upstanding lug

25 will pass through the opening 24 and into the gap 16 within the hollow interior of the latch slide. In operation, after the lug 25 has, through the closing of the frame members, passed through the opening 24, the latch slide is moved inwardly, that is to say, towards the left, so that the front wall part 27 of the latch slide, which adjoins the openings 24 and 20, will move in front of and impinge against the lug 25 so as to retain said lug in the gap and hence prevent any swinging movement of the two frame members from closed position. That portion of the open slot 20 which intervenes between the longitudinal edge 22 of the latch slide and the rear wall 23 of the frame member 10 provides for the accommodation of the upstanding lug during the shifting movements of the latch slide to bring the opening 24 into and out of a position in which the lug 25 will pass therethrough. Under this arrangement, when it is desired to close the frame members, it is necessary only to grasp the knob 19 and pull the latch slide outwardly to the full extent of its movement when the opening 24 will be in proper alignment with the lug 25; whereupon upon moving the frame members into closed position the lug 25 will pass through the opening 24 and into the interior of the latch slide. Then by moving the latch slide inwardly or to the left the lug will be interlocked behind the impinging wall 27 and so retain the frame members in firm closed relation. Manifestly, when, for the purpose of opening the frame members, the latch slide is moved outwardly to the position in which the lug will be released, the latch slide may be permitted to remain in its outward position until the frame members have been closed again. In this way, it is necessary only to pull the latch slide outwardly when the frame members are to be opened and then after they have been closed again to move the latch slide inwardly for effecting the interlocking engagement. The knob 17 obviously serves as a stop for limiting the inward movement of the latch slide. Owing to the frictional contact between the latch slide and the two guide strips, the latch slide will remain in that position to which it is moved. Such frictional engagement is ordinarily sufficient to prevent any accidental rotary movement of the latch slide upon the guide strips; but if desired, positive means may be provided for preventing any rotary movement of the latch slide while permitting its longitudinal shifting movement. In the present instance, to prevent rotary movement, I show a pin projecting from the inner end of the guide strip 14 and slidably fitting in an opening 29 in the stop 26.

Instead of making the guide strips and the latch slide of circular form in cross section, they may in practice be of polygonal form.

The fastening means of my invention,

owing to compactness and to the fact that when the frame members are closed the latch slide occupies a central position at the top of the two frame members, lends itself particularly well for use in connection with frame members of the kind having channels 30 facing outwardly, since there is ample room between the latch slide and the tops of the outer walls 15' and 23' of the respective frame members 10 and 11, for the insertion of the material of the bag into the channels 30 wherein the material is secured to the frame members.

The device of my invention is neat, attractive, symmetrical and well-balanced. It consists of few parts inexpensive to manufacture and to assemble. It also possesses the advantage of ease of operation since the fixed knob 17 may be grasped by the fingers for the firm retention of the bag in the hand during the shifting movement of the latch slide by the seizure of the other knob 19 by the fingers of the other hand.

While the invention has been illustrated and described with some degree of particularity, it is realized that in practice various changes and alterations may be made therein, and further that the invention is capable of embodiment in various types of bag frames. It has been sought herein to illustrate only such an embodiment of the invention as will suffice to exhibit the character of the invention. Reservation is, therefore, made to the right or privilege of changing the form of the details of the construction or otherwise altering the arrangement of the parts without departing from the spirit or scope of the invention or the scope of the appended claims.

40 I claim:—

1. The combination of a pair of parallel frame members movable from and to a position in which they are in closed relation, a hollow elongated latch slide parallel with the frame members, mounted upon one of the frame members for shifting movement longitudinally thereof, said slide operatively occupying a position in which one side thereof overhangs so as to come over the other frame member when the frame members are closed, said overhanging side having therein an elongated bottom opening in communication with the interior of the slide, an upstanding catch lug fixed on the other frame member adapted, when the frame members are closed and on shifting of the slide to latching position, to be received in the hollow interior and in the elongated bottom opening to allow said front part to be brought in front of the lug to interlock therewith and thereby secure the frame members against separation.

2. The combination of a pair of parallel frame members movable from and to a position in which they are in closed relation, an

elongated cylindrical latch slide parallel with the frame members, guide means on one of the frame members on which the slide is mounted for shifting movement longitudinally of the members and providing a space intermediate their free ends, said slide having a front wall bounding the interior space and having communicating side and bottom openings, both in communication with said space, a catch lug fixed on the other frame member adapted, when the frame members are closed, to pass through the side opening into said space to a position in which, on shifting movement of the slide, the bottom opening will pass along the lug and said front wall will engage with the front of the lug for securing the frame members together.

3. Fastening means for a pair of parallel frame members which are movable into closed relation, aligned guides fixed along longitudinal edges to one member to overhang the other member when the members are closed, said guides being spaced to provide a gap between their adjacent ends, a hollow slide sleeve substantially surrounding the guides, the construction of which includes an impinging wall adjoining an entrance opening and a guide opening in communication with the interior of the slide, a lug on the other member adapted, when the members are closed, to pass through the entrance opening into said gap within the sleeve to a position in which, on shifting of the slide, the guide opening will pass along the lug and said impinging wall will impinge on the front of the lug, whereby to secure the members in closed relation.

4. Fastening means for a pair of parallel frame members which are movable into closed relation, aligned guides fixed along longitudinal edges to one member to overhang the other member when the members are closed, said guides being spaced to provide a gap between their adjacent ends, a hollow slide sleeved on the guides the construction of which includes an impinging wall intermediate the ends of the guide adjoining an entrance opening and a guide opening in communication with the interior of the slide, means for moving the slide longitudinally upon the guides, means for preventing turning of the slide upon the guides, a lug on the other member adapted, when the members are closed, to pass through the entrance opening into said gap to a position in which, on shifting of the slide, the guide opening will pass along the lug and said impinging wall will impinge on the front of the lug, whereby to secure the members in closed relation.

5. In a handbag frame having first and second parallel frame members in hinged, and movable in closed, relation; the improvement comprising guide means fixed on one

of the members and providing a gap intermediate the ends thereof, a slide extending substantially the length of said frame member and supported parallel by the guide means with the members, said slide substantially enclosing the guide means and having an opening at one end intermediate the gap ends, and a recessed impinging wall adjoining said opening, the recessed portion forming an open communication with the opening, and a lug projecting from the other of the members for entering the opening of the slide into the gap where, upon longitudinal movement of the slide, the lug is interengaged in the gap by the impinging wall for retaining the frame members securely together while the recessed portion of the impinging wall accommodates the lug.

In testimony that I claim the foregoing as my invention, I have signed my name hereto.

ADAM WAECHTER.
